DESIGN FOR A CLOSURE CAP OR SIMILAR ARTICLE

Joseph R. Fleisch, Clifton, N. J., assignor to Anchor Cap & Closure Corporation, Long Island City, N. Y., a corporation of New York

Application August 5, 1935, Serial No. 57,950

Term of patent 14 years

To all whom it may concern:

Be it known that I, Joseph R. Fleisch, a citizen of the United States, residing in Clifton, county of Passaic, State of New Jersey, have invented a new, original, and ornamental Design for a Closure Cap or Similar Article, of which the following is a specification, reference being had to the accompanying drawing, forming a part thereof.

The figure is a perspective view of a closure cap, illustrating my new design.

I claim:

The ornamental design for a closure cap or similar article, substantially as shown.

In witness whereof, I have hereunto affixed my hand and seal, this 11th day of July, 1935.

JOSEPH R. FLEISCH.
